UNITED STATES PATENT OFFICE

CHARLES HOLLMANN, OF FORT WAYNE, INDIANA

TUBE WINDING MACHINE

Application filed April 8, 1929. Serial No. 353,388.

This invention relates to improvements in machines for forming tubes from strips of paper by winding the strips spirally upon a windle in a manner similar to that disclosed in Letters Patent No. 1,580,369, issued April 13, 1926 to one George U. Brake and myself for tube winding machine, and in Letters Patent No. 1,682,045, issued August 28, 1928, to myself for tube winding machine. The 10 structure herein disclosed, however, differs from those set forth in said Letters Patents in numerous particulars that appear from the following description.

The object of the improvement is to provide a machine for forming a continuous tube from paper strips of indefinite length by winding said strips spirally upon a windle having longitudinally reciprocating tube-supporting bars, an especial object being to 20 provide means whereby each of said sliding bars is permitted to move radially inward in the windle from its normal tube-sustaining position and assume a secondary position during the retracting longitudinal stroke of the 25 bar, and is caused to resume and maintain its outward or tube-sustaining position during its opposite or forward stroke. A further object is to provide means whereby each of said sliding bars is automatically re-positioned in 30 said windle so that the pressure of the tube upon said bar is automatically relieved during the retracting strokes thereof to permit freedom of relative longitudinal movement with respect to said tube and bar.

These objects are accomplished by the construction illustrated in the accompanying drawings, in which:—

Fig. 1 is a fragmentary side elevation showing the rear portion of a machine embodying the invention, a portion thereof being broken away;

Fig. 2 is a similar view showing the head portion of the machine;

Fig. 3 is a side elevation of the driving head 45 of the machine including the windle actuated thereby, portions being broken away;

Fig. 4 is an end elevation of the driving head projected from Fig. 3, the windle and another part being in section;

Fig. 5 is a side elevation of the tail-stock

and parts related thereto, the view being in central section;

Fig. 6 is a front end elevation projected from Fig. 5 and including also the windle which is shown in section;

Fig. 7 is a detail view showing a pair of adjusting rings secured to the tailstock;

Fig. 8 is a fragmentary front elevation of the adjusting rings and corresponding end of the tailstock;

Fig. 9 is a transverse section of the windle and the paper tube as it is formed thereon; and

Fig. 10 is a fragmentary plan view of the windle and the paper strips as they are applied to form a tube thereon.

The invention is comprised of a driving head 1 and a tailstock 2 mounted in axial alinement and spaced apart upon a bed 3 that is supported upon legs 4. The driving head consists of a stationary headstock 5 fixed upon the bed and having at its front end a plate 6 secured thereto by bolts 7. A rod 8 is fixed at its front end in the plate 6 by means of a pin 9 and extends axially through the headstock and to a point within the tailstock.

The rod 8 (Figs. 4 and 6) is formed with a flat face 9 along one side thereof and with the remainder of its external surface uniformly distant from its axial center.

In the headstock is mounted a rotatable spindle 10 through which the rod 8 loosely extends, there being bearings 11 and 12 disposed in the headstock in which bearings the spindle is journaled. Upon the front end of the spindle 10 is keyed a drive-gear 13, and an annular collar 14 surrounds the hub of said gear and is secured in the corresponding end of the headstock against the bearing 12 by which said bearing is held in place. Also,

said collar has disposed therein a felt ring 15 that fits snugly about the hub of said gear, which forms a guard to prevent escape of oil from said bearing. Upon the opposite end of the spindle is keyed a head-block 16, and another annular collar 17 surrounds the hub of said head-block and is secured in the corresponding end of the headstock against the bearing 11 by which said bearing is held in place.

Also, said collar is provided with a 100

felt ring 18 that fits snugly about the hub of the headblock 16, which prevents escape of oil from the bearing 11. The headstock has a chamber 19 located between the bearings 11 and 12 and is supplied with lubricating oil for said bearings through a fixture 20. The headblock 16 is held from longitudinal movement on the spindle by means of a ring 21 that is threaded on the spindle and is seated in said headblock. A tube 22 is positioned in concentric relation with the rod 8 and is provided with a head 23 that is secured to the headblock 16 by means of bolts 24, and is supported at its opposite end upon the rod 8 by a bearing 25. The tube has made therein spaced longitudinal slots 26 disposed in opposite pairs, in which are loosely disposed corresponding bars 27 that have longitudinal and radial movement with respect to the tube, each of which bars has at its forward end an outwardly projecting slotted head 28. The inner edge of each bar bears against the rod 8 when the machine is in action, and pins 29 extend through each bar and project from the sides thereof at points within the tube, which pins limit outward radial movement of the bar. The tube has notches 30 made therein adjacent the sides of each slot to permit passage of the pins when the bars are being placed into position or removed from the tube. The locations of said notches with respect to the length of the tube are at such points as are not reached by the pins during normal operation of the bars and thus unintended removal of the bars is obviated.

A series of brackets 31 are secured upon the outer periphery of the head block 16 disposed in opposite pairs, bolts 32 that extend through said brackets and engage in slots 33 in the headblock being provided to adjustably secure said brackets in place. Each bracket 31 has therein a slide 34 arranged to have longitudinal movement parallel with the corresponding bar 27, and each slide has at its rear end an adjustable lug 35 that affords pivotal support for a lever 36, one end of which extends into the slotted head 28 of the corresponding bar. Each lever has a fulcrum bearing 37 at its outer end on a supporting beam 38 that is adjustably secured upon the corresponding bracket 31 by means of bolts 39 and 40. Each slide has a roller that projects from its inner face into a slotted annular cam 42 that is fixed upon the head stock 5, so that as the headblock is revolved, the slides 34 are reciprocated and corresponding movement is imparted through the medium of the levers 36 to the bars 27. The rotating tube 22 and the reciprocating bars 27 in connection therewith constitute a windle upon which the paper strips 43 to form a tube 44 are wound. The pressure of the paper strips as they are wound upon the windle causes the bars 27 to bear against the rod 8, by which rod in-

ward movement of the bars is limited, and as the rod is stationary and the windle rotates, the bars are moved about the rod and are brought in successive order into contact with the flat face 9 on said rod which permits momentary inward movement of the respective bars during their passage across said face and thus the pressure of the paper tube upon the respective bars during their passage across said face is relieved. The slotted cam 42 and the rod 8 are fixed in connection with the head-stock in such relative positions that the bars 27 have longitudinal movement with respect to the windle toward the tailstock during the passage of said bars around the rod while bearing upon the uniform curved surface thereof, and have retracting longitudinal movement respectively during their passage across the flat face 9 on said rod while relieved of normal pressure of the tube. In this manner is facilitated the retracting strokes of each bar while the paper tube formed on the windle receives normal support upon and is progressed toward the tailstock by the other bars.

A rotating compression appliance is arranged in supported relation with the tailstock 2 for applying pressure externally upon the paper tube after it is formed upon the windle so as to insure adhesion between the paper strips forming the tube and to aid in shaping the tube before it is expelled from the machine. The compression appliance is shown in Figs. 1, 5 and 6 in a position 45 degrees in advance of the position in which the driving head is shown in Figs. 2, 3 and 4, which is done for the sake of convenience of illustration. However, in actual operation, the compression appliance rotates as the driving head rotates and not in advance thereof. The compression appliance consists of a pair of sleeves 45 and 45' having secured therebetween an externally toothed ring 36, which sleeves are supported in axial alignment with the tailstock upon annular bearings 47 so as to have rotary movement, the sleeves project oppositely from the corresponding ends of the tailstock, and each has at its projecting end a flange 48-48' provided with radial slots 49 disposed in opposite pairs, there being guide-ways 50 made in each flange in its slotted portions.

A series of brackets 51-52 are arranged in opposite pairs in connection with the flange 48 of the sleeve 45 that project toward the driving head. Said brackets are shaped to fit into the corresponding guide-ways 50 and are radially adjustable relative to the sleeve. Each bracket 51 has a pin 53 that is operatively related with an adjusting ring 54 that surrounds the corresponding sleeve adjacent its flange, there being spiral slots 55 made in said adjusting ring into which said pins respectively extend so that when said ring is adjustably turned upon the sleeve, said

brackets are accordingly moved radially. Adjacent the ring 54 is positioned upon said sleeve a second adjusting ring 56 provided with a pair of spiral slots 57 into which extend respectively pins 58 that project from the corresponding brackets 52, so that when the ring 56 is adjustably turned upon the sleeve, the brackets 52 will be radially moved accordingly. The adjusting ring 54 has 10 made therein apertures 59 through which the pins 58 respectively extend, which apertures permit adjusting movement of the ring 54 without interference with the pins 58. Thus, the two pair of brackets 51 and 52 are 15 independently adjustable radially relative to the flange 48. The rings 54 and 56 are held in adjusted positions by means of bolts 60 that extend through corresponding apertures 61 in the flange 48 and the adjusting 20 ring 54 and have threaded relation with the ring 56. When the bolts 60 are tightened, said adjusting rings are clamped in place. The apertures 61 permit play of the bolts 60 in the flange and the adjusting ring 54 and 25 allow relative turning movement with respect to the adjusting rings severally and the flange.

Pivoted on each of the brackets 51 and 52 are corresponding levers 62, each of which 30 levers has at its outer end a pivoted shoe 63, and each of said levers has a projecting arm 64 engaged by a compression spring 65 that is disposed between the arm and the flange 48, by the action of which springs the shoes 35 are caused to move toward the axis of the windle which projects therebetween into the tailstock. The shoes 63 are so disposed about the windle as to bear upon the exterior of the paper tube 44, so that each shoe compresses 40 the tube with equal force upon two corresponding windle bars.

A series of brackets 66—67 are arranged in opposite pairs in connection with the flange 48' of the sleeve 45' that project outwardly 45 therefrom. Said brackets are shaped to fit in the corresponding guideways 50 and are radially adjustable relative to said sleeve. Each bracket 66 has a pin 67' that is operatively related with an adjusting ring 68 that 50 surrounds the corresponding sleeve adjacent its flange, in a similar manner to that of the arrangement of the brackets 51 and the adjusting ring 54. Another adjusting ring 69 disposed adjacent the ring 68 is operatively 55 related with the brackets 67, there being a pin 70 on each bracket 67 engaged with the adjusting ring 69 similarly to the arrangement between the brackets 52 and the adjusting ring 56. In this manner the two pair of 60 brackets 66 and 67 are independently adjustable radially relative to the flange 48'. On each bracket 66 and 67 is mounted a roller 71, the axis of which is at right angles to that of the sleeve 45', said rollers being disposed 65 so as to bear upon the exterior of the

paper tube as said tube passes outwardly through the tailstock. The purpose of said rollers is to afford protracted support for the tube and sustain more or less the shape thereof.

The driving head and the compression appliance receive rotary movement from a common countershaft 72 journaled in the bed 3, which countershaft has keyed thereon a pair of pinions 73 and 74, there being an intermediate gear 75 that meshes with the pinion 73 and the gear 13 for imparting movement to the driving head, and a similar intermediate gear 76 that meshes with the pinion 74 and toothed ring 36, by which movement is imparted to the compression appliance. The ratio of the gearing between said countershaft and said driving head and compression appliance is equal so that said driving head and compression appliance revolve 80 together without relative rotary movement.

The countershaft 72 is provided with a clutch mechanism 77 controlled by an operating lever 78 for throwing it into and out of action, and said clutch mechanism is connected with a motor 79 by suitable power transmission mechanism 79 by which it is actuated in the usual manner.

In the operation of the invention the driving head and compression appliance are set 95 in rotary movement by the actuating mechanism therefor, and strips of paper 43 are fed upon the windle in laminated formation and with an adhesive applied between the underlying and overlying strips. The strips 100 are fed to the windle at a suitable angle so as to become wound thereon spirally. As the windle rotates, the windle bars, during the major portion of the revolution of the windle, move longitudinally toward the tailstock causing the paper tube, as it is formed by the strips of paper, to move continuously in the direction of the tailstock. Each windle bar, during a minor portion of the revolution of the windle, when passing across the flat face 9 of the rod 8 recedes toward the axis of the windle, and while thus relieved from the normal pressure of the paper tube, is drawn longitudinally backward to the point of completion of its cycle of action. As only 110 one of the windle bars is relieved and retracted at a time, and full pressure of the tube is maintained upon the other bars, progression of the tube by said other bars is maintained without restraint from the bars 115 during retraction thereof.

As the paper tube progresses through the compression appliance, the shoes 63 bear frictionally upon the exterior surface thereof which cause the tube to conform to the outer edges of the windle bars, and the rollers 71 bear upon the respective flat sides of the tube so that it is supported and its shape protractedly maintained thereby.

What I claim is:—

1. In a paper tube winding machine, a supporting bed; a driving head fixed on said bed; a compression appliance fixed on said bed spaced from and axially alined with said head; a hollow rotary windle axially alined with said head and appliance; and connected at one end with said driving head, the opposite end thereof extending into said compression appliance, said windle having longitudinally and radially movable tube-supporting bars; a stationary rod fixed in said head and extending axially through said windle, one side of said rod having a flat face, the other portion of the exterior surface of the rod about its axis being uniformly distant therefrom, said rod being disposed so as to limit inward radial movement of said supporting bars with respect to said windle; a lever mechanism operatively related with said head and supporting bars whereby said bars are reciprocated longitudinally as said head is revolved; and means for simultaneously rotating said driving head and compression appliance, said appliance having shoes that bear frictionally upon and conform to said supporting bars a paper tube formed upon the windle.
2. In a paper tube winding machine, a driving head; a hollow rotary windle connected at one end with and actuated by said driving head, said windle having longitudinally and radially movable tube-supporting bars; a stationary rod fixed in said head and extending axially through said windle, one side of said rod having a flat face, the other portion of the exterior surface of the rod about its axis being uniformly distant therefrom, said rod being disposed so as to limit inward radial movement of said supporting bars with respect to said windle; a lever mechanism operatively related with said head and supporting bars whereby said bars are successively reciprocated longitudinally as said head is revolved; and means for actuating said driving head.
3. In a paper tube winding machine, a stationary rod having fixed support at one end thereof, one side of said rod having a flat face, the other portion of the exterior surface of the rod about its axis being uniformly distant therefrom; a hollow rotary windle positioned so that said rod extends axially therethrough, said windle having longitudinally and radially movable tube-supporting bars, the inner edge of which bars bear upon said rod whereby inward radial movement of said bars with respect to said windle is limited; and actuating mechanism for rotating said windle and successively reciprocating said supporting bars longitudinally.
4. In a paper tube winding machine, a driving head; a hollow rotary windle axially alined with and actuated by said head, said windle having longitudinally and radially movable tube-supporting bars; a stationary rod fixed at one end extending axially through said windle, against which rod the inner edge of said supporting bars bear when paper strips are wound upon the windle to form a tube, one side of said rod having a flat face whereby said supporting bars are successively permitted to move radially inward during passage across said face; actuating mechanism operatively related with said supporting bars whereby said bars are successively reciprocated longitudinally, said mechanism being timed with respect to the rotation of the windle so that the retracting longitudinal stroke of each bar occurs concurrently with its passage across said flat face when thus relieved of the normal pressure of the paper tube; and means for actuating said head and mechanism.
5. In a paper tube winding machine, a hollow rotary windle having longitudinally and radially movable tube supporting bars; a stationary rod extending axially into said windle, against which rod the inner edges of said supporting bars bear when a paper tube is wound upon the windle, said rod being formed so as to permit said bars to move radially inward severally in successive order at corresponding predetermined stages in the rotary travel of the windle; and means for rotating said windle and successively reciprocating said bars so that the retracting stroke of each bar occurs concurrently with its inward movement while thus relieved from the normal pressure of said tube.
6. A paper tube winding machine having a rotary windle provided with longitudinally reciprocating tube-supporting bars; a rotary compression appliance positioned in axial alinement with said windle, said appliance having shoes disposed in opposite pairs that frictionally bear upon and conform to said bars, a paper tube that is formed upon the windle; means for imparting longitudinally reciprocating movement to said bars in successive order as the windle is rotated; and means related with the windle and compression appliance for imparting rotary movement thereto.
7. A paper tube winding machine having a rotary windle provided with movable tube-supporting bars; means for actuating the windle and bars; a rotary compression appliance positioned in axial alinement with said windle, said appliance having shoes disposed in opposite pairs that frictionally bear upon and conform to said bars a tube that is formed upon the windle; and an annular series of rollers adjustably positioned in connection with said compression appliance, spaced from said shoes, which rollers afford protracted support for said tube in its passage from said windle.
8. A paper tube winding machine having a rotary windle provided with movable tube

- supporting bars; means for actuating the windle and bars; and a rotary compression appliance positioned in axial alinement with said windle, said appliance having shoes disposed in opposite pairs that frictionally bear upon and conform to said bars a tube that is formed upon the windle.
9. A paper tube winding machine having a rotary windle provided with longitudinally reciprocating tube-supporting bars; means for actuating said windle and bars; and a rotary compression appliance positioned in axial alinement with said windle, said appliance having shoes that bear frictionally upon and conform to said bars a paper tube that is formed upon the windle.
10. In a paper tube winding machine having a rotating windle, a compression appliance consisting of sleeves rotatably mounted in axial alinement with said windle, each sleeve having at its outer end an external flange; an annular series of brackets secured to one of said flanges and being radially adjustable thereon; a spring pressed lever pivoted on each bracket; a shoe pivotally connected with each lever and bearing upon a paper tube formed on said windle; another annular series of brackets secured to the other of said flanges and being radially adjustable thereon; a roller in each of the last named brackets, which rollers bear upon and support said tube; and means in connection with each series of brackets and the corresponding flanges for radially adjusting and securing said brackets in place.
11. In a tube making machine having a rotating windle; a compression appliance having a rotating sleeve provided with an external flange; a series of brackets adjustably secured on said flange and arranged in opposite pairs; two rotatably adjustable rings adjacent said flange, each ring having connections with a corresponding pair of said brackets adapted to adjustably move same independently of the other pair of brackets, one of said rings having openings therein to permit freedom of movement of the connections between the other ring and the brackets related therewith; means for clamping said rings in connection with said flange; a series of shoes connected respectively with said brackets, which shoes bear frictionally and conform to said windle a tube wound thereon; and mechanism in connection with the windle and compression appliance for imparting the rotary movement thereto.
12. In a tube making machine having a rotating windle; a compression appliance having a rotating sleeve provided with an external flange; a series of brackets adjustably secured on said flange and arranged in opposite pairs; two rotatably adjustable rings adjacent said flange, each ring having connection with a corresponding pair of said
- brackets adapted to adjustably move same independently of the other pair of brackets, one of said rings having openings therein to permit freedom of movement of the connections between the other ring and the brackets related therewith; means for clamping said rings in connection with said flange; and a series of shoes connected respectively with said brackets, which shoes bear frictionally and conform to said windle a tube wound thereon.
13. In testimony whereof I affix my signature.
- CHARLES HOLLMANN.
